UNITED STATES PATENT OFFICE.

THORSTEN VON ZWEIGBERGK, OF PRESTON, ENGLAND.

CONTROLLER.

No. 861,790.

Specification of Letters Patent.

Patented July 30, 1907.

Application filed November 28, 1906. Serial No. 345,437.

To all whom it may concern:

Be it known that I, THORSTEN VON ZWEIGBERGK, a citizen of the United States, residing at Preston, in the county of Lancaster, England, have invented 5 a certain new and useful Improvement in Controllers, of which the following is a full, clear, and exact description, reference being had to the accompanying drawings.

r^2 and r^3 . In the fourth position, the shunt is open circuited. In the fifth position two sections R' R^2 of the main resistance are cut out, and in the sixth position, the remaining sections R^3 and R^4 of the main resistances are cut out.

60

When the shunt is established around the armature in the first notch on the lowering side, the motor starts, as the field is already excited to its full capacity and the armature starts by the drop in the voltage across the resistance shunt. As soon as the 65 armature speeds up, the counter electro-motive force cuts down the current in the armature, and actually reverses the current when the speed is high enough to overcome the drop tending thereby to reduce the speed of the armature. Then as the controller is moved to the second notch, the armature receives an increased speed, due to the increased drop in the resistance shunt which is again counterbalanced by the increased counter electro-motive force. On the third position, the armature speeds 70

75 still higher and again receives a check by the counter electro-motive force developed. There is a reversed current flowing on each of the 3 first notches, due to the generative action of the motor as soon as the counter electro-motive force has reached a higher value 80 than the drop in the shunt. When it is desired to lower at full speed, the controller is turned successively through positions No. 4, 5 and 6 which cut out the main resistances. If the motor tends to "run away" due to the increased momentum of the falling load, on the 3 last notches it is only necessary to throw the controller back onto the third lowering notch which establishes the armature shunt wherein the reversed current will cause an effective brake.

With my controller, it is possible to efficiently and 90 safely operate a hoist without the necessity of constantly shutting off the controller and applying a band brake when the speed exceeds the safe limit. The electric brake is entirely automatic on the first notches in lowering, and insures against any "run- 95 away".

Having thus described my invention, I claim:

1. A controller for a hoisting motor having raising positions adapted to govern the motor and lowering positions adapted to reverse the motor and establish a resistance 100 shunt about the armature while maintaining connection with the source of current.

2. A controller for a hoisting motor having means for reversing the motor and automatically establishing an electric brake for such reversed motor whereby the load may 105 be lowered under control.

3. A controller for a hoisting motor having raising positions adapted to successively cut out resistance and successive lowering positions adapted to maintain connection with the source of current and also establish a shunt 110 around the armature and thereafter open such shunt.

4. In a controller, the combination of contact members arranged to automatically establish resistance in increas-

10 controller for a hoisting or elevator motor which shall automatically establish an electric brake on lowering, thereby insuring the motor from "running away". I accomplish this by providing a resistance which the controller establishes in shunt around the armature in lowering positions, whereby the counter-electro-motive-force increasingly developed by increasing speed of the armature automatically checks such armature, forming an electric brake and efficiently limiting the armature speed.

20 The invention is hereinafter more fully described and its essential characteristics summarized in the claims.

The drawings are diagrams sufficiently illustrating the invention,—Figure 1 being a development of the controller, and Fig. 2 showing the circuits at successive lowering positions.

In the diagrams, the successive positions are indicated by numerals, there being five raising positions and six lowering positions shown.

30 A single set of contact fingers is illustrated, and it is to be understood that the controller barrel is turned in one direction past said fingers for raising and in the opposite direction for lowering.

The following reference characters are used.

35 S and S' indicate the raising and lowering contact segments respectively and C the contact fingers.

A indicates the armature; F the field of the motor; T the source of current, and G the ground or return line;— R' R^2 R^3 and R^4 the successive sections of the 0 main resistance and r' , r^2 , r^3 , the sections of the shunt resistance.

On the raising positions, the controller gives the usual resistance government,—in the first position connecting the motor in series with the entire resistance, and then successively cutting out resistance until in the final position (No. 5) the resistance is entirely cut out. In lowering, the armature is reversed. On the first position, the resistance is maintained in series with the field of armature and an additional resistance r' is established in a shunt around the armature. On the second notch, the resistance around the armature is increased, the shunt passing in series through the resistances r' and r^2 . In the third position, the resistance is further increased,—the shunt passing through the three resistances r' ,

- ing amount in a shunt around the armature while maintaining connection with the source of current for successive lowering positions of the controller. 50
5. The combination with a hoisting motor and resistances of a controller with contact members having raising positions and having lowering positions arranged to reverse the motor and establish resistances in successively increasing amount in a shunt around the armature. 55
6. In a controller, the combination of contact members arranged to reverse the motor and concurrently establish resistances in increasing amount in a shunt around the armature for successive lowering positions of the controller, and then to open the shunt and finally to govern the field with said shunt open. 60
- 10 15 7. A controller for a hoisting motor having raising positions adapted to successively cut out resistance and lowering positions adapted, while the source of current is connected, to reverse the motor and concurrently establish a resistance shunt around the armature and thereafter open such shunt and cut out the governing resistance. 65
- 20 25 8. The combination with a motor and resistance in series with its field of a controller having contact members arranged to cut out such resistance for raising and arranged to automatically establish other resistance in a shunt around the armature in increasing amount for successive lowering positions of the controller, and then to open the shunt and finally cut out the resistances in series with the field. 70
- 30 9. The combination with a motor and a field resistance, of a second resistance and a controller having positions which successively establish the second resistance in increasing amount around the armature, then open the shunt and cut out the resistance which was in series with the field. 75
- 35 10. A controller for a hoisting motor comprising contact fingers and contact plates adapted to cooperate therewith, one set of such plates corresponding to the elevating rotation of the motor, and the other to the lowering rotation, a main resistance, connections established by the elevating 80 side of the controller for successively cutting out such resistance, a second resistance, and connections established by the lowering side of the controller for successively establishing such second resistance in increasing amount in a shunt around the armature, then opening such shunt and then successively cutting out the main resistance. 85
- 40 45 11. A controller for a hoisting motor having raising positions adapted to connect the motor with the source of current and successively cut out resistance, and having lowering positions adapted to maintain the armature and field in connection with the source of current and with the motor reversed; and to concurrently maintain a shunt circuit about the armature through a resistance, such resistance being gradually increased and then the shunt circuit opened for successive lowering positions. 90
12. A controller for a hoisting motor having raising positions adapted to govern the motor and having lowering positions adapted to reverse the motor and establish a resistance shunt in successively increasing amount around the armature. 95
13. A controller for a hoisting motor having raising positions adapted to govern the motor, and lowering positions adapted to reverse the motor and establish a resistance shunt about the armature while maintaining connection with the source of current, there being subsequent lowering positions which open such shunt. 100
14. The combination with the motor and resistance of a controller having raising positions adapted to cut out resistance, and lowering positions adapted to reverse and short circuit the armature by a resistance shunt, and having a subsequent position adapted to open such shunt. 105
15. A controller for a hoisting motor having raising positions adapted to govern the motor, and lowering positions adapted to reverse the field of the motor and establish a resistance shunt about the armature thereof. 110
16. A controller for a hoisting motor having raising positions adapted to govern the motor, and lowering positions adapted to reverse the field of the motor and concurrently establish a resistance shunt about the armature, successive lowering positions increasing such resistance and subsequently opening such shunt. 115
17. The combination of a motor and resistance in series with its field, of a controller having raising positions adapted to successively cut out such resistance, and having lowering positions adapted to reverse the field of the motor and establish a resistance shunt around the armature while maintaining a connection from the armature to the source of current, successive lowering positions increasing the resistance in such shunt, and subsequently opening the shunt and cutting out the resistance in series with the field. 120
